UNITED STATES PATENT OFFICE.

LEONARD H. WHEELER, OF CHICAGO, ILLINOIS, ASSIGNOR TO STEWART-WARNER SPEEDOMETER CORPORATION, OF CHICAGO, ILLINOIS, A CORPORATION OF VIRGINIA.

VACUUM FEED DEVICE.

Application filed August 24, 1922. Serial No. 583,952.

To all whom it may concern:

Be it known that I, LEONARD H. WHEELER, a citizen of the United States, residing in the city of Chicago, in the county of Cook 5 and the State of Illinois, have invented certain new and useful Improvements in Vacuum Feed Devices, of which the following is a specification, reference being had to the accompanying drawings, forming a part 10 thereof.

The purpose of this invention is to provide a simplified form of vacuum feed device adapted for operation by any means which may be depended upon to furnish a 15 fairly constant and always adequate suction. It consists of certain features and elements of construction hereinafter described and shown in the drawings as indicated by the claim.

20 In the drawings:—

Figure 1 is a diagrammatic side elevation of an apparatus embodying this invention as connected with the engine of a motor vehicle and with the fuel supply tank thereof.

25 Figure 2 is a substantially axial vertical section of the vacuum chamber of the device.

In the diagram of Figure 1 the engine or motor is shown at 1 provided with a carbureter, 2, and fuel supply tank, 3. A suction pump, 4, of any suitable construction 30 is indicated as mounted on the engine base to be driven by the engine so as to furnish at all times a sufficiently strong suction to operate the vacuum feed mechanism. The 35 pump, 4, is connected by a suction pipe, 5, with the vacuum chamber, 6, and the latter is fed from the tank, 3, through a pipe, 7, through which liquid is drawn from the lower tank, 3, when the chamber, 6, is placed 40 under partial vacuum by the withdrawal of air therefrom through the pipe, 5.

45 As the liquid accumulates in the chamber, 6, it automatically causes the closing the valve, 8, which controls the suction connection through the pipe, 5, said valve being carried on a stem, 9, upon which a float, 10, is slidably guided for play between upper and lower stop flanges, 11 and 12, on said stem. At its upper limit the float, 10, closes 50 the valve, 8, and permits the vacuum to be rapidly dissipated through a constantly opened vent port, 13, in the top of the chamber. When atmospheric pressure is restored in the chamber, 6, the liquid discharges by 55 gravity therefrom and permits the float, 10,

to fall to the stop, 12. A cushion spring, 14, receives the impact of the float and stem, 9, as the valve, 8, is unseated in opposition to the suction in the pipe, 5, said spring, 14, tending to guide the action of the device. 60 The lower end of the stem, 9, is guided in the sleeve, 15, supported in an upstanding position from the bottom wall of the chamber, 6, and serving for discharge of liquid therefrom. Outside said bottom wall a 65 flanged fitting, 16, is secured around the opening of the tube, 15, and furnishes a discharge port, 17, and valve, 18, confined within close range of its seat, 17, by means of a cage, 19, screwed into the fitting, 16. 70 Within the cage, 19, a shoulder is formed to receive the feet or lugs, 18^b, of the valve disk, 18, when the latter is released from its seat by cessation of the suction in the chamber, 6. Said valve disk is stiffened 75 against the suction by making its central portion dished or concave at 18^a.

From the cage, 19, the discharge pipe, 20, leads to the carbureter, 2, and said pipe is purposely made of large cross section in 80 proportion to the carbureter and in proportion to the vacuum chamber, 6, so that the pipe, 20, may serve as a reservoir for a quantity of fuel ample to meet the needs of the carbureter, 2, during the suction or filling interval of the cycle of operation of the vacuum chamber, 6. To permit the liquid to flow freely from the pipe, 20, to the carbureter, a vent stack, 21, is connected into the fitting, 19 at 22 and though this connection, 22, is somewhat restricted in cross section, the stack, 21, itself is of comparatively large cross section so that if the external heat tends to vaporize any of the liquid fuel, the vapor can readily bubble through 85 the liquid standing in the pipe, 21, without tending to blow out the liquid contents of the pipe. To avoid interference with the action of the float, 10, a discharge portion, 7^a, of the feed pipe, 7, leading through the 90 top of the vacuum chamber, 6, is bent so as to throw the stream of incoming liquid against the side wall of the chamber, 6, rather than permit it to splash upon the float, 10. 95

I claim:

In a vacuum fuel feeding device comprising a vacuum chamber adapted to deliver fuel by gravity through a discharge orifice in the bottom of the chamber, a fit- 100 105 110 115

ting secured to the bottom of the chamber encompassing said orifice and having a discharge opening substantially larger than said orifice, a pipe reducer fitting screwed onto 5 the first fitting forming a valve chamber below said larger discharge opening, a check valve in said chamber seating upwardly against the first mentioned fitting and a stand pipe connected laterally into said pipe 10 reducing fitting opening into the valve chamber below the valve and extending up along-

side the vacuum chamber to a point above the high liquid level thereof, said stand pipe being opened to atmospheric pressure at the top and being of relatively large cross-section to serve as a fuel reserve chamber for discharge by gravity during the suction intervals of operation of the vacuum chamber. In testimony whereof, I have hereunto set my hand at Chicago, Illinois, this 19th 15 20 day of August, 1922.

LEONARD H. WHEELER.
